W. F. KUCK.
REVERSIBLE BRUSH.

APPLICATION FILED OCT. 26, 1918.

1,345,198.

Patented June 29, 1920.

UNITED STATES PATENT OFFICE.

WILLIAM F. KUCK, OF BOCARATONE, FLORIDA.

REVERSIBLE BRUSH.

1,345,198.

Specification of Letters Patent. Patented June 29, 1920.

Application filed October 26, 1918. Serial No. 259,861.

To all whom it may concern:

Be it known that I, WILLIAM F. KUCK, a citizen of the United States, residing at Bocaratone, in the county of Palm Beach 5 and State of Florida, have invented certain new and useful Improvements in Reversible Brushes; and I do hereby declare the following to be a full, clear, and exact description of the invention, such as will enable 10 others skilled in the art to which it appertains to make and use the same.

This invention relates to new and useful improvements in brushes or brooms of the character in which the brush or broom has 15 a pair of active or brushing ends and has for one of its objects the provision of a head and clamping rod for securing the brush or broom proper to the head and which is so constructed that either end of 20 the broom or brush proper can be brought into active or brushing position.

Another object of this invention is the provision of a reversible brush or broom of the above stated character, which shall 25 be simple, durable and efficient, and which may be manufactured and sold at a comparatively low cost.

With these and other objects in view as 30 will become more apparent as the description proceeds, the invention consists in certain novel features of construction, combination, and arrangement of parts as will be 35 be hereinafter more fully described and claimed.

For a complete understanding of my invention, reference is to be had to the following description and accompanying drawing, in which:—

Figure 1 is a side elevation of a reversible 40 broom or brush constructed in accordance with my invention,

Fig. 2 is a perspective view of a head,

Fig. 3 is a perspective view of a clamp adapted to be connected to the head,

Fig. 4 is a perspective view of the reinforcing means.

Referring in detail to the drawing, the numeral 1 indicates as an entirety a head consisting of a substantially U-shaped member 2 having formed centrally of its web portion a cylindrical sleeve 3 adapted to have secured therein one end of an ordinary handle 4. The arms of the U-shaped member 2 are provided with openings 5 to rotatably receive the ends 6 of clamping rods 55 or members 7. Each of the rods or mem-

bers 7 has its ends offset so that when the rods are assembled together, a substantially rectangular opening is provided to receive the fibers of a broom or brush, and the rods 60 are located intermediate the ends of the fiber. The ends 6 are then inserted within the openings 5 supporting the brush or broom within the head 1. The arms of the head 1 are provided with set screws 8 65 adapted to be turned into engagement with the ends 6 of the rods or members 7 for holding the broom or brush against rotation or turning movement within the head 1, and provides a means wherein either end 70 of the brush or broom can be disposed outwardly of the head, thus permitting either end of the brush or broom to be used.

Clamping plates 9 have angularly related ends 10 adapted to abut each other and are 75 positioned in pairs about the fibers of the broom or brush adjacent each end thereof. The pairs of clamping plates 9 are secured by bolts that extend through the fibers of 80 the broom or brush.

While I have shown and described the preferred embodiment of my invention, it will be understood that minor changes in construction, combination, and arrangement of parts may be made without departing 85 from the spirit and scope of the invention as claimed.

Having thus described my invention, what I claim is:—

A brush comprising a substantially U- 90 shaped head having openings in the ends of the arm portion, means securing a handle to the web portion of the head, a fibrous body disposed between the arm portions and having oppositely disposed brushing 95 ends, a rod disposed on each side of said body and bent inwardly in the direction of each other to form end portions that bear against the edges of said body, the ends of said end portions of the rods being bent at 100 right angles to said end portions and parallel with the remaining portions of said rods and extending into the openings, and set screws carried by the arm portions of the head and adapted to lock the ends of 105 said rods against rotation in the openings.

In testimony whereof I affix my signature in presence of two witnesses.

WILLIAM F. KUCK.

Witnesses:

LEMUEL W. ROYSE,
EDITH SNIDER.
